UNITED STATES PATENT OFFICE.

FRANK A. SATTER, OF CHILI CENTER, NEW YORK, ASSIGNOR, BY DIRECT AND MESNE ASSIGNMENTS, OF ONE-THIRD TO JACOB COHEN AND ONE-THIRD TO JOSEPH COHEN, BOTH OF ROCHESTER, NEW YORK, AND ONE-THIRD TO FRANK A. SATTER, OF CHILI CENTER, NEW YORK.

SAFETY-LAMP.

1,044,256.

Specification of Letters Patent. Patented Nov. 12, 1912.

Application filed November 9, 1911. Serial No. 659,369.

To all whom it may concern:

Be it known that I, FRANK A. SATTER, a citizen of the United States, residing at Chili Center, in the county of Monroe and State of New York, have invented certain new and useful Improvements in Safety-Lamps, of which the following is a specification.

The object of this invention is to provide 10 an improved oil burning safety lamp.

A further object of my invention is to provide an oil tank in which the oil is securely inclosed and separated from the wick by which the oil is burned, the oil being fed 15 from said tank to the wick only at the rate at which it is burned.

Another object of my invention is to hold 20 the oil confined so that if the lamp is upset it cannot flow out of the lamp or on to the wick at any greater rate of speed than when the lamp is in upright position.

Another object of my invention is to interpose between the oil chamber and the wick on which the oil is burned one or more feeding wicks by which the oil is fed to the wick 25 on which it is burned.

Another object of my invention is to regulate 30 the flow of oil from the tank to these feeding wicks, which flow will be increased as the lamp is turned up and will be decreased as the lamp is turned down.

These and other objects of my invention, 35 will be fully described in the specification, illustrated in the drawings and pointed out in the claims.

In the accompanying drawings, Figure 1 represents a vertical section through the lamp, on the line 1^x—1^x of Fig. 2. Fig. 2 represents a horizontal section on the line 40 2^x—2^x of Fig. 1. Fig. 3 is a detail sectional view of the central cylindrical chamber of the lamp, showing the wicks in a modified arrangement. Fig. 4 is a sectional view of the central cylindrical chamber of the lamp, 45 showing a round wick interposed between the two feed wicks. Fig. 5 is a detail perspective view of the device that regulates the feed of the oil to the feed wicks. Fig. 6 is a perspective view of the device for raising 50 the wick and for raising the valve through which the oil is fed.

In the accompanying drawings, like reference numerals indicate like parts.

In the drawings 1 indicates the base of the

lamp having substantially the same shape 55 as is found in tubular lanterns. This base is essentially a hollow shell. Inclosed within this shell is an oil tank 2 into which the oil is fed through the filler 3, which filler is closed normally by the screw cap 4. Above 60 and below the oil tank 2 are the air chambers 5 and 6, which chambers are connected by the passages 7 and 8 that extend through the oil tank. These passages 7 and 8 are preferably flat tubes having a rectangular cross section, as is illustrated in Fig. 2. Central of the oil tank 2 is the cylindrical tube 9 which connects the upper and lower air chambers 5 and 6. Extending 65 in a complete loop up through the tubes 7 and 8 and down through the central opening 9 are the endless wicks 10 and 11, which wicks are stationary and are not intended to move, and are intended to be used as feeding devices or as feed regulating devices, or as 70 part of the feed regulating system of the lamp.

Through the cylindrical tube 9 near its base are made the openings 12 and 13, through which oil can escape from the oil 80 tank 2 into the cylindrical tube 9, and as fast as it escapes through these openings 12 and 13 the oil is absorbed by the wicks 10 and 11. The opening 12 is opened and closed by the collar 14 which encircles the 85 central tube 9 and which is raised and lowered to open and close the opening 12 by a mechanism which I will now describe.

Mounted in the oil tank is the tube 15 which tube extends through the upper shell 90 of the base of the lamp and through the top of the oil tank and ends near the bottom of the oil tank. This tube is open throughout its whole length except where it is closed by the packing material 16 and 17, 95 wrapped around the stem 18 with which it moves. Through this packing material extends the stem 18 which at the top is provided with a rack 19. On top of the lamp is placed the burner 20 equipped with the 100 ratchet wheels 21 and 22, rigidly connected to the ratchet shaft 23. This ratchet shaft at its outer end has the knurled wheel 24 rigidly fastened thereto, by which the lamp may be turned up or down. Also fastened 105 to this shaft is the gear wheel 25 which meshes with the rack 19, by which the stem 18 is raised or lowered with the wick. The

stem 18 at its bottom has the cross bar 26 and above this cross bar the stem is perforated or drilled with a hole 27. The stem is preferably a round rod about three-sixteenths of an inch in diameter, the hole 27 being preferably about an eighth of an inch in diameter. The stem 18 has a ring cut therein around the rod both above and below the hole 27, on which the packing material 16 and 17 is wound and by which it is held in place by the rod 18 with which rod it moves up and down in the tube 15. The tube 15 is perforated at 28 and 29. From the perforation 29 leads a tube 30 which 15 extends to the central cylindrical tube 9, to which it is connected so as to encircle the hole 13 so that no oil can pass through the hole 13 except such as passes through the tube 30. When the stem 18 is in the position 20 shown in Fig. 1 the oil can pass through the openings 28, 27 and 29 into the tube 30 and through the opening 13 into the tube 9 on to the wick 11. The oil cannot pass up through the tube 15 from the bottom for the 25 packing material 17 shuts off the oil from passing in that direction. Neither can the oil rise in the tube 15 through the opening 27 as the packing material 16 prevents it. The tubes 30 and 15 are connected together 30 so as to completely surround the opening 29 in the tube 15.

The stem 18 carries a cross bar 26 at its lower end, on one end of which is carried the collar 14 which encircles the inner tube 9. 35 This collar is cut away at 31 where it passes over the tube 30. This collar closes the opening 12 but does not close the opening 13, the feed of oil through which opening 13 is controlled through the opening 27 and 40 the stem 18.

In the bottom of the oil tank 2 is a vent opening 32 having an inverted cone shape. On the out-turned end of the cross bar 26 is a cone shaped plug 33 adapted to work 45 out of and into the vent opening 32 as the stem 18 is raised and lowered. When the stem 18 is raised the vent opening 32 is opened and air can bubble up into the oil tank through this opening as the oil flows 50 out through the tube 30 and through the opening 12. In this way the flow of oil from the oil tank on to the feed wicks 10 and 11 is regulated.

If desired the opening 12 may be dispensed with or closed up, in which case the collar 14 may be omitted. In this case the oil will be fed solely through the tube 30 and the opening 13 in the manner above described. The air space 6 at the bottom 60 of the tank will be filled with wool or cotton which will absorb any excess of oil that may escape into the air chamber, by which such oil will be fed to the wick 10, so that both wicks 10 and 11 will receive a supply 65 of oil through the tube 30.

Mounted in the burner 20 is the wick 34 on which the oil burns in the burner 20. This wick 34 comes in contact with the wicks 10 and 11 near the top of the oil tank, as shown in Fig. 1. The feeding wicks are held in contact with the burning wick by means of the cone 35 which is perforated at 70 36 and 37, through which perforations the wicks 10 and 11 pass. By this cone the feeding wicks may be held in any position 75 against the burning wick.

As shown in Fig. 2, the cone 35 holds the wicks 10 and 11 close together so that the burning wick 34 lies between them and parallel thereto instead of perpendicular thereto as shown in Fig. 3, and as shown in Fig. 4 the cone holds the wicks 10 and 11 against the round or tubular wick 38, by which the oil is burned in the burner. 80

It will thus be seen that none of the wicks 85 of the lamp are immersed directly in the oil in the oil tank 2, but that oil is fed to the wicks only through openings the size of which may be varied according to the size 90 of the lamp and the rate at which it consumes oil. These openings and the regulation of the flow of oil through them are adapted to pass the oil on to the wicks only as fast as the burner consumes it, so that there is little or no free oil in the bottom 95 of the lamp or in the space that directly communicates with the burner that can run out of the lamp or into the burner in case the lamp is upset.

I have shown and described endless stationary wicks, but it will be understood 100 that any form of stationary wick that is held in place to absorb the oil as it is fed from the oil tank and feed it in turn to the moving wick, comes within the spirit 105 and scope of my invention and is the full mechanical equivalent of the endless wicks described and claimed. The endless wick is made by putting an ordinary long single wick in place and sewing the abutting or 110 overlapping ends together.

Having thus described my invention, what I claim as new and patentable is as follows:

1. In a safety lamp the combination of a base, an oil tank isolated therein, one or 115 more adjustable openings from said oil tank, stationary wicks mounted in said base adjacent to said openings to absorb the oil that flows through said openings, a burner, a movable wick mounted in said burner 120 making contact with said stationary wick to absorb the oil therefrom.

2. In a safety lamp the combination of a base, of an oil tank mounted in said base, leaving an air space above and below said 125 oil tank in said base, a plurality of openings through said oil tank connecting the air spaces at the bottom and the top of said base, endless stationary wicks extending around through said openings, a burner 130

8. The combination in a safety lamp of a base, an oil tank mounted in said base with 50 an air space in said base below said oil tank, a central opening through said oil tank communicating with the air space in said base, a tube extending down through said base into said oil tank, a second tube connecting said first named tube with an opening into said central opening, openings in the bottom of said first named tube through which the oil can flow into said second named tube and into said central opening, 60 means for opening and closing said openings to regulate the flow of oil from the oil tank into said central opening.

9. The combination in a safety lamp of a base, an oil tank mounted therein with an air space in said base above and below said tank, endless stationary wicks mounted in 65 said base and encircling portions of said oil tank.

10. The combination in a safety lamp of a base, an oil tank mounted therein with an air space in said base above and below said tank, endless stationary wicks mounted in 70 said base and encircling portions of said oil tank, one or more stationary wicks mounted in said central opening, a movable wick making absorbing contact with said stationary wick or wicks.

11. The combination in a safety lamp of a base, an oil tank mounted therein, a wick mounted to move in said base and excluded from said oil tank, means to raise and lower 75 said wick, a regulator to govern the flow of oil from said tank on to said wick, said wick raising means and said regulator being connected together to operate in unison, the oil being fed by gravity from the tank above to 80 said wick in the base, thus avoiding an accumulation of an excess of oil at said wick.

12. The combination in a safety lamp of a burner, a wick mounted to move therein, an oil tank closed against said movable wick, a 85 stationary wick having a portion thereof below said tank and adapted to receive oil therefrom, through a valve controlled opening and feed it to said movable wick.

In testimony whereof I affix my signature 90 in presence of two witnesses.

FRANK A. SATTER.
